UNITED STATES PATENT OFFICE.

SPENCER H. PHELPS, OF EVANSVILLE, INDIANA.

DISK JOINTER.

1,162,645.

Specification of Letters Patent.

Patented Nov. 30, 1915.

Application filed May 4, 1915. Serial No. 25,728.

To all whom it may concern:

Be it known that I, SPENCER H. PHELPS, a citizen of the United States, and a resident of Evansville, in the county of Vanderburg and State of Indiana, have invented 5 a new and Improved Disk Jointer, of which the following is a full, clear, and exact description.

The disk jointer, as ordinarily employed 10 on plows, is usually supported by a single standard which is deficient in holding the disk with sufficient rigidity to withstand the severe strains of use. The supporting means usually employed also leave much to be desired in lacking means to properly position the disk, especially in the case of a twisted plow beam.

Objects of my invention are to provide 20 an improved means to sustain the disk with increased rigidity, and to provide for adjusting the securing means in various directions and at various angles to compensate for any deformity in the plow beam, and to position the jointer in proper relation to the 25 plow to insure a clean path for the plow by cutting the trash and at all times turning the trash toward the furrow far enough to be completely turned under by the plow.

The invention will be more particularly 30 explained in the specific description following.

Reference is had to the accompanying 35 drawings forming part of this specification, in which similar characters of reference indicate corresponding parts in all the views, and in which:

Figure 1 is a side elevation of a disk jointer and its securing means embodying 40 my invention, showing the same applied to a plow beam; Fig. 2 is a plan view; Fig. 3 is a transverse vertical section on line 3—3 Fig. 1; Fig. 4 is a detail transverse vertical section of the jointer and the journal therefor; Fig. 5 is a face view of the beam plate; Fig. 6 is a transverse vertical section of one 45 of the saddle rings for the standards; and Fig. 7 is a view similar to Fig. 6 but showing the saddle ring after having been turned through an angle to bring a different seating portion thereof in position to receive a 50 standard.

In constructing a practical embodiment of 55 my invention in accordance with the illustrated example, the disk jointer 10 may be in general of any approved form. The jointer is suspended from two standards 11

having offset or cranked lower ends 11^a connected by a girt 12, as hereinafter explained in detail. The girt receives the journal of the jointer, here shown as in the form of a pin 13 which passes through a boxing 14 in the hub 10^a of the disk and in the girt 12. The boxing 14 has an annular flange 14^a received between the girt 12 and the hub of the jointer, and has upper and lower lips 14^b receiving the girt 12 between them. The journal pin receives a nut 15 beneath which is a dust cap 16 on the hub.

The girt 12 has sleeve bearings 17 at the ends thereof in which the cranks 11^a of the standards 11 are adapted to turn. Pins 18 or equivalent devices on the cranks 11^a below the sleeve 17 hold the girt 12 against displacement. The respective standards 11 are mounted to be turned on their axes 75 through any desired angle necessary to give relative movement to the respective cranks 11^a, so that the disk 10 may be properly positioned with respect to the plow beam, regardless of any deformity in the plow beam 80 A. In the present instance the upper ends of the standards 11 have square ends 11^b to receive a wrench.

To secure the standards 11 in position on the plow beam A, a beam plate or disk 19 is 85 adjustably secured in any suitable manner to the beam, as for instance, by the bolts 20 of clips 21. Associated with the beam plate 19 at the front face thereof is a saddle ring or seat ring 22 which on the front has concaved depressions 23 arranged in alined pairs, the respective pairs of seats being disposed on various diametrical lines around the ring. The saddle ring is of tapered form, as clearly shown in Figs. 6 and 7, the 90 body shown in cross section in Fig. 6, as will be noted, being of reduced thickness, so that the lower portion has a greater projection at the front. In Fig. 7, on the other hand, which is supposed to represent the 95 said ring after having been turned to an angle, the thicker portion of the body is uppermost, while the thinner portion is lowermost. Thus, in turning the saddle rings on their axes through the desired angle, particular seats 23 will be brought into position to properly receive the standards and position the latter properly with respect to a vertical line, regardless of twisting or like deformation in the plow beam 100 A. To hold the said ring in adjusted position on the beam plate 19, said ring has an 105

annular series of teeth 24 at the rear side thereof and mating teeth 25 are produced on the front face of the beam plate 19.

In order to hold the standards 11 in the seats 23 of the saddle rings 22, I employ 5 U-bolts 26, the arms of which extend forwardly through curved slots 27 in the beam plate 19, and through the rings 22 and receive clip members or clamp plates 28 that 10 present concave bearing members 28^a to bear against standards 11 at the front. The connection is completed by nuts 29 on the arms of the U-bolts 26. By the described construction the loosening of the nuts 29 to a 15 sufficient extent will permit of turning the U-bolts through an angle about the axes of the saddle rings 22 and beam plates 19. At the same time either saddle ring may be turned about its own axis to bring particular seats 23 thereof in position to receive a 20 standard.

It will be obvious that the clamps on the beams can be readily moved forward or back to conform to the distance between centers of the cranks, and the clamp then made fast to the beam after the jointer has been set to the required position. The advantage 25 of the adjustment provided and the simplicity of effecting the same are of great practical importance, since the plow beam is not always plumb over the line of the plow, and any defect in this respect may be readily compensated for by throwing the respective 30 crank portions of the standards to the right or left more or less with respect to each other and to the straight line of travel, as 35 conditions may require.

Having thus described my invention, what I claim as new and desire to secure by Letters Patent, is:

1. In means for supporting a disk plow jointer on a plow beam, a pair of standards adapted to be turned about their axes and having cranked portions, means for securing 40 the standards in adjusted position on a plow beam, and a girt connecting the cranked portions of the standards, to be positioned by a relative movement of said cranked portions when the standards are turned on their 45 axes, said girt having means to support a disk jointer.

2. In means for supporting a disk plow jointer, a pair of standards having cranked portions, means to secure the standards to 50 a plow beam to be optionally turned on their axes, and a girt connecting the cranked portions of the standards and provided with a bearing to journal the jointer.

3. In means for supporting a disk plow 55 jointer, a pair of standards having cranked portions, means to secure the standards to a plow beam, to be optionally turned on their axes, said means including a seat member for each standard, each seat member being provided with depressed seats at various

inclinations to the face of the said member and at angles to one another, said member being mounted to turn about an approximately horizontal axis to bring either seat in position to receive a standard, and a girt 70 connecting the cranked portions of the standards and provided with a bearing to journal a disk jointer.

4. In means for supporting a disk plow jointer, a pair of standards, means to revolvably support a disk jointer on the standards and means to adjustably clamp the standards to a plow beam, said latter means including seat members against which the standards are held, said members having depressed seats at various inclinations to the face of the said members and at inclinations to one another, the seat members being turnable on their own axes to present any of the 85 seats thereof to the standards.

5. In means for supporting a disk plow jointer, a pair of standards, means carried by the standards to revolvably support a disk jointer, separate clamp devices for each standard, and in which the standard is optionally turnable on its own axis, and adjustable vertically, each clamp device including a saddle member presenting an inclined face formed with seats for the standards, said seats being at angles to one another, and means to secure the said clamp devices on a plow beam.

6. In means for supporting a disk plow jointer, a pair of standards having cranked portions, a girt connecting the said cranked 100 portions, said girt being formed to support a plow jointer, and means to separately secure the standards to a plow beam to be slidably adjustable toward and from each other, said standards being optionally turnable about their own axes, to variously position the cranked portions thereof.

7. In means for supporting a disk plow jointer, separate standards having cranked portions, means connecting the cranked portions and provided with a bearing for a jointer, elements having means to separately and adjustably clamp the same to a plow beam, a seat member on each of said elements, said seat member having seats thereon disposed at various inclinations to the face of the member and at various angles to one another, said seat members turning on approximately horizontal axes relatively to the said separate elements whereby to 110 present either of the seats to the standards, U-boats engaging the said plow beam elements and extending outwardly through the said seat members, clamp bars on the arms of the U-boots bearing against the standards 115 at the outer sides thereof, and nuts on the U-boots outside of the said clamp bars.

8. In means to support a plow jointer, separate standards having cranked portions, means to secure said standards to a plow 130

beam to permit of their being optionally turned on their own axes, to vary the relations of the cranked portions, and a girt having means to sustain a jointer and provided with sleeve bearings receiving the cranked portions of the standards.

9. In means to support a plow jointer, separate standards having cranked portions, means to secure said standards to a plow beam to permit of their being optionally turned on their own axes, a girt having bearings for the cranked portions of the standards, and bearing means for a disk jointer, said bearing means being carried by

15 the girt and including spaced lips embracing the girt.

10. In means to support a plow jointer, separate standards having cranked portions,

Copies of this patent may be obtained for five cents each, by addressing the "Commissioner of Patents.
Washington, D. C."

means to secure said standards to a plow beam to permit of their being optionally turned on their own axes, a girt having sleeves at the end thereof to receive the cranked portions of the standards, a jointer disk having a hub, a box in said hub having spaced lips between which the central portion of the girt is received, and a journal pin extending through said hub box and girt.

In testimony whereof I have subscribed my name to this specification in the presence 30 of two subscribing witnesses.
